(57) **CLAIM**

The ornamental design for a bottle stopper, as shown and described.

DESCRIPTION

FIG. 1 is a front view of a bottle stopper embodying the present invention.

FIG. 2 is a top view of the bottle stopper of FIG. 1.

FIG. 3 is a bottom view of the bottle stopper of FIG. 1.

FIG. 4 is a left side view of the bottle stopper of FIG. 1; and, FIG. 5 is a rear view of the bottle stopper of FIG. 1.

The bottle stopper is symmetrical so that it has the same appearance from both sides.
